UNITED STATES PATENT OFFICE.

JOHN O. ANDERSON, OF CASS LAKE, MINNESOTA.

WICK RAISING OR ADJUSTING DEVICE FOR SHAVING-MUGS.

1,124,250.

Specification of Letters Patent. Patented Jan. 12, 1915.

Application filed July 20, 1914. Serial No. 852,054.

To all whom it may concern:

Be it known that I, JOHN O. ANDERSON, a citizen of the United States, residing at Cass Lake, in the county of Cass and State 5 of Minnesota, have invented a new and useful Wick Raising or Adjusting Device for Shaving-Mugs; and I do hereby declare the following to be a full, clear, and exact description of the invention, such as will 10 enable others skilled in the art to which it appertains to make and use the same.

This invention relates to a new and useful improved wick adjusting or raising device particularly designed for use in connection with shaving mugs, as hereinafter set forth.

The invention comprises further features and combination of parts, as hereinafter set forth, shown in the drawings and claimed.

20 In the drawings:—Figure 1 is a vertical sectional view through the shaving mug or cup. Fig. 2 is a transverse sectional view on line 2—2 of Fig. 1.

Referring to the drawings, 1 designates 25 a shaving mug or cup, which may be of any suitable construction or configuration having a concaved bottom 2 provided with a conical or tapering portion or peak 3 constituting a flame spreader or deflector upon 30 the under portion of the concaved bottom, and acting to spread or deflect the flame substantially evenly upon the under face of the bottom.

The lower portion of the mug or cup is 35 provided with a flared flange 4 forming a supporting base for the cup, and threaded within the lower portion of the cup is an oil or fuel container or receptacle 5, for the reception of oil or the like. Forming 40 an integral part of the bottom of the container or receptacle 5, and rising upwardly is a central tube 7 constituting an air tube, the upper convexed end 8 of which is perforated, as shown at 9 to permit the air to 45 percolate therethrough into the combustion chamber 10, so as to mix with the fumes of the fuel from the wick 11, thereby in this manner insuring a more efficient flame. Also rising from the bottom of the receptacle 50 or container 5, and forming an integral part thereof is a tube 12 of considerable less diameter than the tube 7, and disposed between the tube 7 and the vertical mov-

able wick carrying thimble 13, which is provided with spurs 14, extending into the 55 wick, so as to cause the wick to move with the thimble.

Mounted in the tube 12 is a rod 15 having upon its upper end a worm 16, which meshes with the teeth 17 of the thimble, so 60 as to adjust the thimble vertically, and with it the wick.

The lower end of the rod 15 is provided with a thumb button 18, whereby the rod may be rotated, when it is desired to adjust 65 the thimble and the wick.

The top of the container or receptacle 5 is provided with a filling opening 19, closed by the plug 20.

Extending downwardly into the container, 70 and forming an integral part of the top thereof is an interiorly threaded flange 21, with the teeth of which a tube 22 (which is provided with threads 23) meshes. The upper end of the tube 22 is constructed with 75 an annular flange 25, and by the adjustment of the tube 22, the upper peripheral portion of said tube may be arranged closer or farther from the burning periphery of the wick, thereby to a certain extent controlling 80 the frame.

To gain access to the interior of the combustion chamber for any purpose whatsoever, such as for the adjustment of the tube 22, or for trimming the wick a sliding closure 26 is provided, whereby the opening 27 may be covered and uncovered.

In the wall of the mug or cup adjacent the combustion chamber are perforations 28, in order to produce a proper combustion of 90 the fuel. The lower end of the wick spreads as shown, so that the oil or fuel will readily feed up the wick by capillary attraction.

Projecting from the bottom of the container or receptacle 5 is a member 30, whereby the container or receptacle may be screwed in place into the mug or cup. The lower portion of the wall of the mug below the bottom of the container is provided with a series of perforations 31, so as to permit 100 air to find its way into and through the central tube 7. The water and the soap are deposited in the cup or mug, and the burner lighted, and the usual agitation of the water and soap is performed by the use of the 105 brush, and as the lather thickens the same

is heated, and by virtue of the flame the same is kept warm or at the proper temperature, while the person is shaving.

The invention having been set forth, what is claimed as new and useful is:—

In a wick adjusting mechanism for a heating device, a fuel container having an inwardly and downwardly extending threaded flange, a tube threaded within said flange, a thimble carrying a wick telescopically mounted in said tube and having exterior upwardly extending spurs to pierce the wick, said thimble being provided with interior worm threads, an elongated tubular bearing rising from the bottom of the container on the interior of the thimble, the bottom of the container having a handle, and a device

mounted in said bearing and extending through said handle and provided with means of connection with said worm threads 20 for adjusting said thimble and the wick vertically, said tube being designed to be adjusted downwardly to frictionally co-operate with the wick to retain the wick in engagement with the upwardly extending 25 spurs.

In testimony whereof I have signed my name to this specification in the presence of two subscribing witnesses.

JOHN O. ANDERSON.
